UNITED STATES PATENT OFFICE.

GEORGE P. KELLER, OF HOBOKEN, NEW JERSEY.

BUFFING OR POLISHING WHEEL.

1,087,781.

Specification of Letters Patent.

Patented Feb. 17, 1914.

Application filed August 7, 1913. Serial No. 783,483.

To all whom it may concern:

Be it known that I, GEORGE P. KELLER, a citizen of the United States, and a resident of Hoboken, in the county of Hudson and State of New Jersey, have invented a new and Improved Buffing or Polishing Wheel, of which the following is a full, clear, and exact description.

The invention relates to buffing or polishing wheels formed of a plurality of folded pieces of muslin or other fabric material.

The object of the invention is to provide a new and improved buffing or polishing wheel arranged to prevent the peripheral face of the wheel from unraveling and thus insuring long life of the wheel, and to allow using the wheel until the fabric pieces are practically used up.

In order to accomplish the desired result use is made of a plurality of folded fabric pieces, each piece being bias cut and in the form of an elongated endless band having a scalloped edge, the band being doubled up lengthwise to form a primary fold, which is doubled up transversely to form overlying second folds, which are doubled up to form partly overlying third folds, the doubled-up side of one folded fabric piece extending between the second folds of the next following fabric piece, the scalloped edges of each piece overlying one the other and the scalloped edges of the several pieces forming the peripheral face of the wheel.

A practical embodiment of the invention is represented in the accompanying drawings forming a part of this specification, in which similar characters of reference indicate corresponding parts in all the views.

Figure 1 is a plan view of the fabric material from which the wheel pieces are cut; Fig. 2 is an enlarged plan view of one of the pieces prior to folding; Fig. 3 is a similar view of the same after being doubled up lengthwise to form the primary folds; Fig. 4 is a similar view of the same after being doubled up transversely; Fig. 5 is a similar view of the completely folded piece; Fig. 6 is a face view of one side of the wheel with the pieces assembled; Fig. 7 is a similar view of the other side of the wheel; Fig. 8 is a face view of one of the outer fabric disks; Fig. 9 is a face view of the wheel with the covering disk partly broken out to show the center disk and the folded pieces; Fig. 10 is a plan view of a fabric wheel piece of modified form; and Fig. 11 is a face view of

several fabric pieces assembled and with one of the fabric pieces folded back and portions of the other pieces broken out.

The pieces A for forming the wheel are cut at bias from a piece of fabric material B, as shown in Fig. 1, and each piece is in the form of an elongated endless band having a scalloped edge. The end scallops A' and A² are semicircular and the intermediate scallops A³, A⁴ and A⁵, A⁶ are each in the form of a quarter circle. The opening A⁷ of the endless band is produced by cutting out two circular pieces eccentric relatively to the end scallops A' and A², as plainly shown in Fig. 2. The outer walls of the openings intersect the centers of the scalloped ends A', A², and the inner edges of the cut-out portions are arranged tangentially relatively one to the other, the triangular portions adjacent the tangential inner ends being also cut out to produce the opening A⁷, as shown in Fig. 2. The piece A of the shape described is first doubled up along its longitudinal center line indicated in Fig. 2, to provide a primary fold, shown in Fig. 3, with the corresponding scalloped edges in register with each other. The doubled-up piece is now doubled up transversely, as shown in Fig. 4, to form overlying second folds, which in turn are doubled up to form partly overlying third folds, as indicated in Fig. 5. By the arrangement described the several scallops each in the form of a quarter circle are in register with each other and form the peripheral face of the piece, and eight such folded pieces are arranged in a circle to form the buffing or polishing wheel.

By reference to Fig. 11 it will be noticed that the individual folded pieces are assembled in such a manner that the doubled-up side of one folded fabric piece extends between the second folds of the next following folded fabric piece, the registering scalloped edges of the several pieces forming the peripheral face of the wheel. By arranging the individual eight pieces in the manner described, the outer edge of one of the third folds of each piece extends approximately radially, as plainly indicated in Fig. 6, while the outer edge of the other third fold extends at an obtuse angle from the peripheral face of the wheel, as indicated in Fig. 7. By the arrangement described the individual pieces are symmetrically arranged and interlocked with the peripheral edges of the pieces presenting a

bias cut peripheral surface, so that the material is not liable to unravel while being used for buffing or polishing purposes.

In the manufacture of the wheel the face 5 of the assembled sections shown in Fig. 7 is overlaid with a central disk C of a strong fabric material so as to reinforce the center portion of the assembled pieces, and covering disks D are then placed on each face 10 of the assembled pieces and the several parts are stitched together in the usual manner so as to form a unit. Any number of such units may be assembled on an arbor between the end clamping plates in the usual manner 15 so that further description of the same is not deemed necessary.

If desired, more than two scallops A³, A⁴ or A⁵, A⁶ may be used as indicated in Fig. 10, in which two more clamps A⁸ are 20 interposed between the edges A³, A⁴ and A⁵, A⁶. In this case two more circular pieces are cut out of the blank to form the elongated opening A⁷. The piece shown in Fig. 10 is first doubled up lengthwise, then 25 doubled up in a transverse direction the same as above described in reference to Figs. 2, 3 and 4, and then is doubled up again in a transverse direction and finally once more in a similar direction until all the 30 scalloped edges are in register one with the other, and the folded pieces are assembled in a circle in the same manner as above described so that further description of the same is not deemed necessary.

Having thus described my invention, I 35 claim as new and desire to secure by Letters Patent:

1. A buffing or polishing wheel, comprising

ing a plurality of folded fabric pieces, each piece being bias cut and in the form of an 40 elongated endless band having a scalloped edge, the band being doubled up lengthwise to form a primary fold, which is doubled up transversely to form overlying second folds, which are doubled up to form partly overlying third folds, the doubled-up side of one folded fabric piece extending between the second folds of the next following fabric piece, the scalloped edges of each piece overlying one the other and the scalloped edges 50 of the several pieces forming the peripheral face of the wheel.

2. A buffing or polishing wheel, comprising a plurality of folded fabric pieces, each piece being bias cut and in the form of an 55 elongated endless band having a scalloped edge, the band being doubled up lengthwise to form a primary fold, which is doubled up transversely to form overlying second folds, which are doubled up to form partly overlying third folds, the doubled-up side of one folded fabric piece extending between the second folds of the next following fabric piece, the scalloped edges of each piece overlying one the other and the scalloped edges 60 of the several pieces forming the peripheral edge of the wheel, the outer edge of one of the third folds of each piece extending approximately radially.

In testimony whereof I have signed my 70 name to this specification in the presence of two subscribing witnesses.

GEO. P. KELLER.
